UNITED STATES PATENT OFFICE.

OSCAR H. PIEPER AND ALPHONSE F. PIEPER, OF ROCHESTER, NEW YORK.

DESIGN FOR A STANDARD FOR X-RAY APPARATUS.

60,059.

Specification for Design.

Patented Dec. 20, 1921.

Application filed November 18, 1920. Serial No. 425,004. Term of patent 14 years.

To all whom it may concern:

Be it known that we, OSCAR H. PIEPER and ALPHONSE F. PIEPER, both citizens of the United States, residing at Rochester, in the county of Monroe and State of New York, have invented a new, original, and ornamental Design for a Standard for X-Ray Apparatus, of which the following is a specification and of which the accompanying drawing is a representation.

Figure 1 is a side elevation of a standard for an X-ray tube showing our new design.

Fig. 2 is a top plan view of the same, and Fig. 3 is an end elevation.

We claim:

The ornamental design for a standard for X-ray apparatus, as shown.

OSCAR H. PIEPER.
